DEVICE FOR PILING UP PREFORMED
BINDER AND/OR WRAPPER LEAVES
FOR CIGARS, CIGARILLOS, OR
BUNCHES THEREOF

Everardus W. C. van Buul, Eindhoven, Netherlands, assignor to N. V. Vereenigde Tabaksdriëen Mignot & De Block, Eindhoven, Netherlands

Application January 31, 1950, Serial No. 141,371
In the Netherlands March 3, 1949

4 Claims. (Cl. 131—105)

1

The invention relates to a device for piling up preformed binder and/or wrapper leaves for cigars, cigarillos or bunches thereof.

In machines for making bunches, cigarillos or cigars the binder leaf or the wrapper leaf is usually picked up from a cutting matrix and brought into a rolling mechanism having rollers or a rolling apron. This transport of the tobacco leaf is effected by a holder provided with a suction head or other holding means.

It has not yet been proposed to cut the binder and the wrapper leaves out of tobacco leaves in quite another part of the factory, to pile the preformed binder or wrapper leaves up in a magazine and to put the filled magazine in the machine for making the bunches, cigarillos or cigars. This is due to the fact that hitherto it was not possible using a suction or leaf adhering holder to transfer the leaves with certainty one after the other from the pile contained in the magazine to the rolling mechanism. The difficulty is that tobacco leaves are moist and stick together and that many of the leaves have holes so that leaves lying beneath the uppermost leaf are taken up together with the said uppermost leaf.

The invention has for its object the avoidance of the difficulties met with in transferring a preformed binder or wrapper leaf from a magazine, and thus to permit the use of magazines filled with binder and/or wrapper leaves in bunch or cigar making machines. In essence, it involves locating the leaves that are placed into a magazine one upon the other crosswise in at least two predetermined directions.

The invention also relates to a magazine for a pile of preformed binder and/or wrapper leaves, said magazine having parts for the lateral confinement of the pile of leaves and said parts permitting said leaves to be placed one upon the other crosswise in at least two predetermined directions only. It has been found that if the leaves lie crosswise one upon the other they cover each other so slightly that the suction head or other holding means of the leafholder picks up the uppermost leaf of the pile only.

Advantageously, a device is used which is provided with means for the rotary or oscillatory support of the magazine and with a driving mechanism adapted to rotate or oscillate the magazine periodically through an angle or angles equal to the angle or angles between the predetermined directions in which the leaves are permitted to lie in the magazine. In such an arrangement the suction head or the other holding means of the leafholder need not be rotated

2

intermittently or be oscillated to pick up the leaves out of the magazine. In order to facilitate the picking up operation the magazine may be provided with a vertically movable bottom plate.

5 According to the invention a device for filling a magazine for a pile of preformed binder and/or wrapper leaves lying crosswise one upon the other may be provided with one or more movable leafholders adapted to transport the leaves one after the other from a support, e. g. a cutting matrix to a place above or in the magazine, and may be so constructed, that each time, after a leaf has been delivered into the magazine, the latter will be rotated through a predetermined angle.

10 15 The invention also provides a device for taking periodically a leaf out of a magazine and consists of one or more movable leafholders adapted to take the leaves one after the other out of said magazine and to transport them to a place, e. g. a rolling mechanism, where they are used for making bunches, cigarillos or cigars. Said device is so constructed that each time, after a leaf has been taken out of the magazine, the latter is rotated through a predetermined angle. In this device stop members are provided which are disposed between the leafholder and the magazine, said stop members permitting the leaves to be picked out of the magazine in only one predetermined position, and those leaves that are oriented at an angle to this position will abut the stop and thus be held in the magazine when the uppermost leaf is taken out. A stop member may, for example, constitute a fixed plate having an elongated aperture the size and form of which corresponds to that of the leaf to be picked out of the magazine.

30 35 The invention permits the picking up of a binder leaf and a wrapper leaf alternately out of one and the same cross-shaped magazine and thereby permits the construction of machines for making cigars consisting of a filler, a binder and a wrapper in a relatively simple way.

40 45 For the elucidation of the invention reference is made to the drawing, in which:

Fig. 1 is a vertical sectional view of a magazine according to the invention,

Fig. 2 is a plan view of the magazine according to Fig. 1,

Fig. 3 is a plan view of a magazine of a different shape,

Fig. 4 shows diagrammatically a plan view of a device for filling a magazine according to Fig. 1,

Fig. 5 is in elevation a diagrammatical view of a device for periodically taking a binder or a

wrapper leaf out of a magazine according to Fig. 1, and

Fig. 6 is a plan view of a detail of Fig. 5.

In the drawing 1 is a magazine of which, as is shown in Fig. 2, the side walls confine a cross-shaped space. The side walls serve for the lateral confinement of a pile of binder and/or wrapper leaves 2, contained in the magazine, in which pile said leaves lie crosswise one upon the other. It will be obvious that by this manner of piling up the leaves the areas with which successive leaves contact each other are as small as possible.

The magazine 1 is rotatably supported about a vertical axis by a fixed support 3. It is adapted to be oscillated through an angle of 90° by means of a rod 4 which, at one end, is coupled with an arm 5 secured to the magazine (Fig. 4), and at the other end is connected to a lever 7 which is rotatably supported about a shaft 6. The lever 7 is held in contact with a cam disc 9 by a spring 8. The cam disc is mounted on a shaft 10 and is so shaped that during each revolution of shaft 10 the magazine 1 remains during a short time in one end position and during a short time in the other end position. Provided in the magazine 1 is a bottom plate 11 on which the preformed tobacco leaves are piled up. This plate is attached to a vertical rod 12 passed through the bottom of the magazine 1 and adapted to be moved up and down by means of a lever 14 rotatably supported about a shaft 13. The lever 14 is kept in contact with a cam disc 16 mounted on a shaft 17 by means of a spring 15 (Fig. 5).

The preformed tobacco leaves may be placed, instead of crosswise, in the shape of a V or of another open geometrical figure or in the shape of a triangle or another closed geometrical figure one upon the other. Fig. 3 is a plan view of a magazine in which the tobacco leaves lie one upon the other according to a quadrangle.

Fig. 4 illustrates diagrammatically a device for filling the magazine according to Figs. 1 and 2 with preformed leaves and also shows how the magazine is oscillated periodically between two end positions. In this filling device the mechanism 13, 14, 15, 16, 17 for moving the bottom plate 11 up and down according to Fig. 5 is omitted. During the filling operation the bottom plate 11 remains at the bottom of the magazine. The filling operation itself is carried out by an oscillatory holder 19 which has a head 20 and is rotatably mounted on a shaft 18. This head is, in a manner well known and therefore not shown, connected to a suction pipe and provided with a perforated lower surface for holding a picked up tobacco leaf. The suction head 20 is oscillated between the magazine 1 and a cutting matrix 21, well known in the art. In order to obtain the oscillating movement of the leaf holder the arm 19 is connected by a link 22 to a lever 23, which is also rotatably supported about shaft 6. The lever 23 is held by a spring 24 in contact with a double cam 25 mounted also on shaft 10. The cam 25 is so shaped that, during each revolution of shaft 10, the leafholder 19, 20 oscillates one time. A tobacco leaf is placed by hand on the cutting matrix 21 and by means of rollers, known per se and therefore not shown, a wrapper or a binder leaf is cut out from said tobacco leaf.

After this cutting operation the suction head 20 is brought above the cut out binder or wrapper leaf, so that this leaf is drawn by suction against the perforated surface of the suction head 20. Thereupon, the suction head is moved to a position vertically above the magazine 1, which at

this time is in one end position. In order to have the leaf dropped from the suction head into the magazine, the suction is neutralised by closing the suction pipe. After having dropped the leaf the suction head 20 is returned to the cutting matrix 21 on which, in the meantime, another binder or wrapper leaf has been cut out. During the return movement of the suction head the magazine is rotated through an angle of 90°. If thereafter the suction head is returned to the magazine it will drop the held leaf crosswise on the uppermost leaf contained in the magazine. During the next movement of the suction head to the cutting matrix the magazine is rotated back through an angle of 90°, etc. This operation is repeated till the magazine is completely filled.

The machine diagrammatically shown in Fig. 5 is adapted to make bunches, cigarillos or complete cigars and is provided with a leafholder 27 in which a partial vacuum is kept up and which is supported by a rotary shaft 26. The lower surface of the suction head is perforated, so that it is permitted to take a wrapper or a binder leaf 2 out of the magazine 1 by suction and to transport said leaf to a rolling mechanism consisting of a number of parallel rollers 28. Each time that the perforated area of the suction head is brought into the position vertically above the magazine 1, the bottom plate 11 (Fig. 1) is released by the cam disc 16 permitting the spring 15 to lift said plate and press the pile of binder or wrapper leaves 2 against the suction head 27.

Mounted between the suction head 27 and the upper edge of the magazine 1 is a plate 30 (Fig. 6) having an aperture 31 the shape of which corresponds to that of a binder or a wrapper leaf. In the machine according to Fig. 5 the magazine 1 is periodically oscillated through an angle of 90° in the manner as is shown in Fig. 4, relating to the filling device, so that alternately a leaf lying in one position and the next leaf lying in the other position in the magazine are brought into the right position to be taken up by the suction head 27. Only if a leaf be brought into the said right position, will the aperture 31 in the fixed plate 30 permit a leaf to pass. The leaf which lies under the uppermost leaf in the magazine is directed at right angles to the uppermost leaf and the aperture 31 in plate 30, so that it cannot be taken out of the magazine together with said uppermost leaf and hence all but the top leaf of the leaves is held in the magazine. Consequently, the plate 30 prevents the suction head 27 of the leafholder from taking up more than one binder or wrapper leaf simultaneously. Instead of a plate, other stop members, e. g. two parallel rods, may be used for holding the pile in the magazine.

The magazine may be alternately filled with a wrapper leaf and a binder leaf. It is not necessary that the leaves piled up crosswise be oriented at right angles. Also, other angles may be used, so that the leaves may cross each other in more than two different directions. Further, if the wrapper leaves or the binder leaves have a diametrically symmetrical shape the magazine need not to be oscillated about its axis, but it may be intermittently rotated in one and the same direction through angles, say of 90°.

What I claim is:

1. A tobacco leaf holder and transfer device comprising a frame, a receptacle rotatably mounted in the frame, said receptacle being cruciform in shape in horizontal cross-section and having a bottom provided with a bearing open-

ing, a plate positioned above said bottom, a rod secured to the plate and extending through the opening, a lever pivoted on the frame, a cam positioned on an axis parallel to the axis of the lever pivot and capable of rotation, the exterior surface of the cam at all times being in contact with the lever, resilient means retaining the lever in engagement with the cam, and means at the end of the rod connected to the lever, whereby actuation of the lever will cause reciprocation of the rod and an oscillatable suction device for removing top leaves one at a time from the receptacle, the oscillatable suction device and the reciprocatable rod being so synchronized that the instant suction is applied to the top leaf, the supporting plate will be moved away from the bottom of the receptacle.

2. A tobacco leaf holder and transfer device comprising a frame, a receptacle rotatably mounted in the frame, said receptacle being cruciform in shape in horizontal cross-section and having a bottom provided with a bearing opening, a plate positioned above said bottom adapted to support a plurality of tobacco leaves contained in said receptacle in cross-wise arrangement, a rod secured to the plate and extending through the opening, a pivoted lever arranged to move said rod upon movement of said lever, a rotatable cam having an exterior surface engageable with said lever, resilient means retaining the lever, said cam being adapted to cause said lever to pivot in a predetermined circle whereby to effect reciprocation of said rod, and an oscillatable suction device for removing top leaves one at a time from the receptacle, the oscillatable suction device and the reciprocatable rod being so synchronized that when suction is applied to the top leaf the supporting plate will press the top leaf against the suction device.

30

35

40

3. A tobacco leaf holder and transfer device as defined in claim 2, further comprising means for rotating said receptacle through a predetermined angle upon movement of said suction device.

4. A tobacco leaf holder and transfer device comprising a frame, a receptacle mounted in said frame for rotation about a vertical axis and adapted to hold a pile of preformed oblong tobacco leaves, said receptacle including means defining a space which is cruciform in shape in horizontal cross section and has two intersecting storage areas adapted to receive the leaves of said pile with their longitudinal axes in alternate cross-wise relationship, a movable leaf carrier mounted in said frame, said leaf carrier being in the form of a suction device for removing top leaves one at a time from the receptacle, means for effecting relative movement between said leaf carrier and said receptacle, and means for periodically rotating said receptacle through an angle equal to the angle included between the longitudinal axes of the two intersecting storage areas of the receptacle, said receptacle-rotating means being synchronized with the movements of the movable leaf carrier, whereby each of the intersecting storage areas is alternately brought into cooperation with said leaf carrier.
